UNITED STATES PATENT OFFICE

ADOLF H. SCHAFFERT, OF YOUNGSTOWN, OHIO, ASSIGNOR TO TRUSCON STEEL COMPANY, OF YOUNGSTOWN, OHIO, A CORPORATION OF MICHIGAN

WINDOW STRUCTURE

Application filed March 20, 1929. Serial No. 348,574.

In the manufacture of metal window frames and sash of the type in which the sash is swung to an open position, the limitations of the size of the parts have been such that it has been impossible to open the sash fully without cutting away the corners of the sash. This, however, causes other difficulties for when the sash is closed, the hood or weathering-strip on top of the frame must not only be lengthened, but the hood must be formed on a distinctive angle because the path of the upper end of the window is on an arc such that the window will not clear the under edge of the hood. This angle of the hood has the disadvantage that it allows air to pass beneath it and over the sash since the latter does not tightly fit. Another difficulty has been that the notched corners leave exposed cracks that are objectionable for the same reasons.

The object of the present invention is to provide a structure in which a novel sash mounting is provided that insures the end of the window seating itself properly with respect to the hood, avoids the necessity of notching the corners of the sash, and allows the window to open beyond a 90 degree angle.

In the accompanying drawings;

Figure 1 is a vertical sectional view of a portion of a metallic window frame, in which 30 is a movable ventilator sash, the latter being shown in its closed position.

Figure 2 is a similar view, but with the sash partly open.

Figure 3 is a view similar to Figures 1 and 35 2, but with the sash fully open.

Figure 4 is a horizontal sectional view on the line 4-4 of Figure 3.

Figure 5 is a detail view on an enlarged scale of the sliding pivotal mounting of the 40 sash on the frame.

Figure 6 is a detail perspective view of the slide block and its carrying spring.

Figure 7 is a perspective view of the side block and the associated portion of the 45 spring.

In the embodiment disclosed, the window-frame includes vertical side bars 8, a sill member 9 having an abutment flange 10, and a top rail 11. Suitably fixed to the under- 50 side of this top rail is a plate 12 having an

outer downturned flange 13 that constitutes a depending hood and has its lower end slightly outset, as shown at 14. The vertical side bars 8 are provided with inset longitudinally disposed guide ribs 15.

The window sash is rectangular in form and consists of side bars 16, a bottom rail 17 provided with an outer depending weathering flange 18, and a top rail 19 provided with an inner upstanding flange 20. It will be noted by reference to Figure 1 that this sash fits snugly into the window frame with the lower flange 18 abutting the outer edge of the lower rail 9 and the upper flange 20 against the inner edge of the upper rail 11. It will also be noted that the outer edge of the top rail 19 of the sash fits behind the hood 13-14.

Links 21, pivoted at their lower ends to the lower portions of the side bars 8 of the frame, as shown at 22, have their upper ends pivoted as illustrated at 23 to the upper portions of the side bars 16 of the sash. The upper end of the sash has sliding mountings in the frame. To this end leaf springs 24

are secured at their lower ends by rivets 25 or other fasteners to the outer sides of the side bars 16 of the sash. These springs are slightly offset as shown in Figures 4 and 6 and their upper free ends project beyond the top rail 19 of the sash, said projecting upper ends being journaled on the gudgeons 26 of slide blocks 27, grooved as illustrated at 28, to receive the guide ribs 15 of the side bars 8 of the frame. Preferably the gudgeons have washers 29 interposed between the springs and the guide block. By reference to Figures 4 and 7 it is to be noted that the gudgeons 26 are offset from the grooves 28 and on the side toward the sash so that the pivot axis of

the springs and consequently of the sash is on the outer side of the window frame. As a consequence the corners of this sash, indicated at A, are brought out sufficiently far when the sash swings to open position, that

the sash will pass a right angular position with respect to the frame and will actually move to substantially 94 degrees as distinguished from a 75 degree opening heretofore obtained in a structure of this kind.

More than that it has been found that the upper end of the sash will clear the lower edge of the hood 14, without the necessity of having the hood projected outwardly to any material degree and said upper end of the sash will slide to a snug closing fit. More than that inasmuch as the corners of the sash at A do not have to be notched or cut away, the entire upper edge of the sash will be housed and no exposed cracks left at the corners.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What I claim, is:

1. In a window structure, the combination with a frame having a vertical side guideway, a swinging sash that operates in the frame, links connecting the sash and frame to cause its swinging movements, a slide block engaged with the guideway, and a mounting for the sash having a pivotal mounting on the slide block at one side of the vertical center of the guideway, said mounting coacting with the links to cause the upper end of the sash to abut against and be stopped by the frame after said upper end has passed to a position lower than the lower end of the sash.

2. In a window structure, the combination with a frame having a vertical side guideway, a swinging sash that operates in the frame, links connecting the sash and frame to cause its swinging movements, a slide block engaged with the guideway, and a mounting for the sash having a pivotal mounting on the side of the vertical center of the slide block that is nearer the sash, said mounting coacting with the links to cause the upper end of the sash to abut against and be stopped by the frame after said upper end has passed to a position lower than the lower end of the sash.

3. In a window structure, the combination with a frame having a vertical side guideway, a swing sash that operates in the frame, links connecting the sash and frame to cause its swinging movements, a slide block engaged with the guideway, and a leaf spring mounted on the sash and having a pivotal mounting on the side of the vertical center of the slide block that is nearer the sash.

4. In a window structure, the combination with a window frame having an end wall provided with a hood and a side wall provided with a longitudinal inwardly extending guide rib, a block slidable on the rib and having a groove in its rear side that receives

the same, a swinging sash, links pivotally connecting the sash and frame, and a spring mounted on the sash and having a pivotal connection with the block that is offset with respect to the groove and guide rib.

5. In a window structure, the combination with a window-frame having a top end wall provided with a depending hood and side walls provided with longitudinal inset guide ribs, a swinging sash, blocks having grooves in their rear sides that slidably receive the ribs, said blocks being located above the upper corners of the sash, leaf springs secured to the opposite sides of the sash and having pivotal connections at their upper ends with the inner sides of the blocks and offset on the latter toward the sides that are adjacent the hood, links connecting the sash and frame to cause the sash to swing, said offsetting of the pivotal connections permitting the upper end of the sash including the corners, to enter behind the hood and also to move downwardly to permit the upper corners of the sash to abut the sides of the frame at a line that is lower than the outer or free end of the sash when the sash is swung to open position.

In testimony whereof, I affix my signature.

ADOLF H. SCHAFFERT.
